(57) **CLAIM**

The ornamental design for automated nucleic acid analysis detector, as shown and described.

DESCRIPTION

FIG. 1 is a first perspective view according to our new design;

FIG. 2 is a front view thereof;

FIG. 3 is a rear front view thereof;

FIG. 4 is a left side view thereof;

FIG. 5 is a right side view thereof;

FIG. 6 is a top view thereof;

FIG. 7 is a bottom view thereof;

FIG. 8 is a second perspective view of our new design; and,
FIG. 9 is an open state view of our new design.

The broken lines depict portions of the automated nucleic acid analysis detector that form no part of the claimed design.
